UNITED STATES PATENT OFFICE.

DANIEL E. TENNEY, OF WOBURN, MASSACHUSETTS, ASSIGNOR TO WOBURN MACHINE COMPANY, OF WOBURN, MASSACHUSETTS, A CORPORATION OF MASSACHUSETTS.

SPREADING ROLL FOR HIDE-WORKING MACHINES.

Application filed April 20, 1925. Serial No. 24,406.

To all whom it may concern:

Be it known that I, DANIEL E. TENNEY, a citizen of the United States, residing at Woburn, in the county of Middlesex, State 5 of Massachusetts, have invented a certain new and useful Improvement in Spreading Rolls for Hide-Working Machines, of which the following is a specification, reference being had therein to the accompanying 10 drawings.

The invention has relation in general to machines for treating hides and skins, such as fleshing machines, unhairing machines, putting-out machines, wringers, and others 15 of the like class; and in particular to devices for spreading and flattening the hides or skins while they are undergoing treatment in such machines.

The object of the invention is to provide 20 improved means for straightening out and spreading a hide or skin in a machine of the said class at points where fullness presents itself, and in particular for straightening out or spreading the shanks and neck of the 25 stock, whereby to eliminate tendency of these parts to pleat and crease as they pass between the bed-roll and the working cylinder, and thereby remove danger of damaging the grain.

30 The invention comprises the combination with a working cylinder, and a working-support for the hide being treated, movable into working relations with said cylinder and separable therefrom to permit the hide 35 or skin to be introduced between them, of a spreading roll also movable into open and closed relations with the working cylinder, adapted to press the hide or skin against the surface of the working cylinder, and 40 rotating reversely with respect to the direction of movement of the hide.

An illustrative embodiment of the invention is represented in the drawing, in which Fig. 1 is a view in vertical section from 45 front to rear of a machine having the said embodiment incorporated therein. Figs. 2 and 3 are sectional views showing modifications.

In Fig. 1 of the drawing is shown only so 50 much of the essential elements of a hide working machine as is necessary for an understanding of the invention, and its application in connection therewith.

At 1 is shown one of the end-frames serving as the principal supports for the main 55

working parts of the machine, the said end-frames as usual sustaining the bearings for the different rolls and cylinders which operate on the hides or skins. These parts in this instance comprise a working cylinder 2, 60 as it is called, having a helically bladed periphery of a character suitable for the performance of the particular type of work upon the hide or skin for which the machine is intended, a bed-roll 3 serving as a movable 65 support for the hide or skin to hold it up to the action of the working cylinder 2, and feed-rolls 4, 4, against which by the bed-roll 3 the hide or skin is clamped so as to hold the same securely while being acted upon 70 by the working cylinder. In usual practice, as is well known, the bed-roll 3 is covered with a cushion of rubber, and by its rotation in unison with the feed-rolls 4, 4, the hide is fed relative to the working cylinder 75 2 so as to cause all portions of the hide to be acted upon by the said cylinder. The directions in which the working cylinder and the respective rolls are rotated, and in which the hide or skin is fed, are indicated by 80 arrows.

To provide for the convenient introduction of the hide or skin into position to be operated upon, the rolls of machines of the type dealt with herein usually are made capable of movement bodily relative to one another, so as to enable them to be separated for convenient insertion of the hide, and then closed together to cause the hide to be acted upon. The particular roll that is 85 mounted for movement is the bed-roll 3 in the case of the illustrated mechanism. For allowing this movement, the bearings or journal-boxes 5 in which the shaft 6 of the bed-roll 3 revolves are adapted to move back 90 and forth within ways or guides 8 in the end-frames. The means for effecting the movement in question at the will of the operator is not shown, inasmuch as it is not a part of the present invention. It may comprise in practice any one of the arrangements known in the art. 100

In carrying the invention into effect I employ a spreading roll 19, which I locate in such relation to the bed-roll 3 as will provide for smoothing out and spreading the hide to present it flat and free from wrinkles to the action of the working cylinder 2 as it passes between the said cylinder and the bed-roll 3. In the illustrated machine, this 110

spreading roll 19 is placed below the bed-roll 3 and is arranged so that when the bed-roll and spreading roll occupy their closed position, as in the drawing, the spreading roll holds the hide or skin in contact with the working cylinder 2. Inasmuch as the hide or skin must be entered between the said spreading roll 19 and the working cylinder, provision is made for separating these 5 two by mounting the spreading roll upon swinging arms 20 which are mounted to swing on centers near the bottom of the machine; in the present instance concentrically with the shaft 21. To move the spreading roll 19 toward and away from the working cylinder, in unison with the bed-roll, the arms 20 in this instance are formed with forks, indicated at 23, which fit portions of the journal-boxes 5 of the bed-roll shaft 6, 10 so that movement of the bed-roll 3 will be accompanied by simultaneous bodily movement of the spreading roll 19.

The spreading roll is preferably covered with rubber. In accordance with the invention, it is rotated to cause its periphery to move in a direction opposite to the direction of travel of the hide, so as to render it effective in smoothing out any wrinkles or folds, spreading out slack places, and properly disposing the neck and shanks of the hide or skin. To provide for such rotation, it is mounted in this instance in journal-boxes or bearings 24 in connection with the swinging arms 20, and 15 equipped with a V-grooved pulley 30 fixed upon its shaft 301, around which pulley runs a V-belt 300 driven by a second V-grooved pulley, 302, fixed on the rotating shaft 21, and kept tight by a binder sheave 31 carried on an arm 32 adjustably clamped to one of the swinging arms 20. This belt rotates the spreading roll in the direction indicated by the arrow, namely so that its periphery moves oppositely with respect to the direction of movement of the hide or skin in being fed by the action of the bed-roll and feed-rolls. In order that the spreading roll may bear the hide or skin yieldingly against the blades of the working cylinder, the journal-boxes or bearings 24 are backed up by springs 25 confined within caps 26 which are secured to the arms 20 by screws 27, 27; the journal-boxes or bearings 24 being equipped with 20 spindles 28 which project through the tops of caps 26 and have nuts 29 applied outside said caps, to constitute stops to limit the movement of the journal-boxes or bearings within their guideways under the push of their springs. This yielding mounting of the journal-boxes or bearings of the spreading roll, together with the rubber covering thereon, prevents injury to the hide or skin which is being operated upon, 25 through the jamming of folds, thick places,

or other irregularities of the hide between the spreading roll and the working cylinder.

The positioning of the spreading roll so that it will have working relations with the working cylinder 2 at a point somewhat in 70 advance of the bite or line of engagement between the bed-roll 3 and the working cylinder, gives the hide or skin an opportunity to flatten out under the action of the spreading roll before being compressed between the said roll and the working cylinder, as well as causes the working cylinder to do work upon the hide or skin at the point of tangency of the spreading roll therewith, and in addition over the entire 75 area of hide between said point and the bite of the bed-roll and the working cylinder.

The approach of the spreading roll to the working cylinder is so limited that the periphery of the spreading roll is prevented from actual contact with that of the working cylinder.

Fig. 2 shows a spreading roll 191 having a brush-like periphery. Fig. 3 shows one, 192, having its periphery constituted by a series of blades.

What I claim as my invention is,—

1. The combination with a working cylinder, and a work-support against which the working cylinder operates in acting upon a hide or skin, movable into working relations against said cylinder and separable therefrom to permit a hide or skin to be introduced between them, of a spreading roll by which the hide or skin is pressed against the surface of the working cylinder in advance of the squeeze between the work-support and said cylinder, and means 95 for producing reverse rubbing and spreading action of said spreading roll upon the portion of hide or skin approaching said squeeze.

2. The combination with a helical working cylinder, and a work-support and backing against which the working cylinder operates in acting upon the hide or skin, movable into working relations against said cylinder and separable therefrom to permit a hide or skin to be introduced between them, of a spreading roll adapted to press the hide or skin against the working cylinder, similarly movable and separable, and driving means for rotating said roll to act upon the hide or skin reversely with respect to the direction of rotation of the working cylinder.

3. The combination with a working cylinder, and a support for a hide or skin being treated, movable into open relations with respect to said cylinder and also into closed relations against the latter, of a spreading roll adapted to press the hide or skin against the working cylinder, also movable into open position and into closed

relation with the said cylinder, and means for rotating said roll to act reversely upon the hide or skin while being fed through the machine.

- 5 4. The combination with a working cylinder, and a support for a hide or skin being treated, movable into open relations with respect to said working cylinder and also into closed relations against the latter,
10 of a spreading roll and means for rotating the same to act upon the hide or skin re-

versely with respect to the direction of travel of the hide or skin while being operated upon by the working cylinder, said spreading roll operably combined with said movable support to be moved toward the working cylinder to press the hide or skin into engagement therewith, or away therefrom, upon corresponding movements of the movable support. 15

DANIEL E. TENNEY.
